UNITED STATES PATENT OFFICE

CAROLUS LEVON EKSERGIAN, OF DETROIT, MICHIGAN, ASSIGNOR TO EDWARD G. BUDD MANUFACTURING COMPANY, OF PHILADELPHIA, PENNSYLVANIA, A CORPORATION OF PENNSYLVANIA

ROLLER LEVELER

Application filed April 3, 1929. Serial No. 352,302.

My invention relates to a roller leveling machine of the type shown in the prior Patent No. 1,649,706 granted to G. L. Kelley and myself on November 15, 1927.

It is an object of my invention to generally improve the automatic operation of a machine of this type, to increase the life of the machine, to speed up the production without subjecting the movable parts to undue shock or strain, to incorporate safety features into the machine to guard against prolonged holding up of the machine for repairs, to provide a machine more flexible in operation and more readily adaptable to the regulation and control of the work, and more precise, positive, durable, and efficient in operation than the machines of this type as heretofore constructed.

The features by which these objects and other objects are attained will become apparent from the following detailed description when read in connection with the accompanying drawings forming a part of this specification, and will be pointed out in claims appended at the end of the specification.

In the drawings,

Fig. 1 is a front elevation of the machine embodying my invention and the drive therefor with parts of the base frame broken away;

Fig. 2 is an end elevation of the same;

Fig. 3 is a sectional view, the section being taken in the central longitudinal vertical plane of the machine approximately on the line 3—3 of Fig. 1.

Fig. 4 is an enlarged detail view of a portion of the front of the machine, showing the relation between the automatic control and safety switch mechanisms and the draft or pinch rolls.

Figs. 5 and 6 are detail longitudinal vertical sectional views taken approximately on the lines 5—5 and 6—6 of Fig. 4 and showing, respectively, the automatic control and safety-switch mechanisms.

Fig. 7 is a detail sectional view of the relay mechanism controlling the movements of the working element or brake roll.

Figs. 8 and 9 are further detail views of the control and motor mechanism of the brake roll, Fig. 8 being a plan view of the

operating cylinder and associated parts, and Fig. 9 a longitudinal sectional view through the same.

Fig. 10 is a detail end view of the operating cylinder and the associated parts.

The Figure 11 is a sectional view taken longitudinally through a pressure applying medium employed in connection with the present invention, and

Fig. 12 is a diagram of various electrical control circuits employed in connection with the present invention.

The machine embodying the invention comprises a suitable base frame 10, upon the left-hand side of which, Fig. 1, is mounted the roller leveler mechanism proper, and on the right hand side the motor M and transmission mechanism T for driving the rolls.

The roller leveler proper consists of the usual upper and lower series of straightening rolls 12 between which the sheet is passed after it passes through the working rolls at the front of the machine. The lower series is supported in upper side frame members 13 secured to the base frame and the upper series, which is arranged, as usual, in staggered relation to the lower series in the direction in which the sheet is fed through the machine, is mounted in adjustably mounted end frames 14, as usual, to permit adjustment of the upper series of rolls toward or from the lower series.

At the front end of the series of staggered rolls, are mounted the two pairs of draft or pinch rolls 16 which are adapted to grip the sheet fed between them with sufficient force to prevent it from slippage with respect thereto, under the action of the working or brake roll 17. To provide for the ready assembly or dis-assembly of these rolls with the side members 13 of the machine, the latter are provided with the spaced guiding and retaining slots 18 open at the top, in which the bearing blocks 19 of the rolls are guided and retained and through the open upper ends of which the rolls and blocks may be readily removed or inserted.

In a forwardly projecting portion of the side frame members 13 are mounted a pair of hold down rolls 20, spaced from the pinch

rolls a distance sufficient to permit the brake roll 17 to rise up between them to give the sheet passing between the pinch and hold down rolls the proper amount of working.

5 These rolls are spaced (see Fig. 6) a distance slightly greater than the thickness of the sheets being fed to permit the sliding of the sheet between the rolls, both when it is originally fed to bring it into operative engagement with the pinch rolls, and also when it is subsequently engaged by the brake roll 17. A guide plate 21 guides the sheets being fed to the rolls 20. These rolls are longitudinally offset in the direction of movement of the sheet, the upper roll being in advance of the lower, this offsetting having two purposes, to avoid a heavy drag of the sheet on the guide when it is engaged by the brake roll which might result in the marring of the sheet and causing rapid wear of the guide plate, and also, to obtain a sharper bending of the sheet around the upper roll, when the brake roll rises, which enables the sheets to be more strongly worked.

10 The brake roll 17 also has its ends mounted in sliding blocks 22 movable in guides 23 in the frame side members 13, which are also open at the top to permit easy removal of the brake roll and its mounting blocks, when desired.

15 It is actuated from a shaft 24 journalled in the front of a transverse frame member 25. The ends of this shaft are provided with crank arms 26 which are connected by links 27 to the sliding bearing blocks 22 for the roll. At an intermediate portion the shaft is provided with a crank arm 28 connected by a link 29 extending through an opening in the frame member 25 to the actuating motor and control mechanism M' removably mounted as a unit on the base, and removable and insertable as a unit from and into the frame through an opening at the rear thereof.

20 This motor and control mechanism embodying a number of novel improved features will now be described. The mechanism is shown most clearly in Figs. 8, 9 and 10. The motor mechanism comprises a casting 30 having a widened base portion adapted to be secured to the main base of the machine and a compressed-air operated cylinder 31 in which operates the two-part piston 32, 32'. The part 32' of the two part piston is threadedly mounted on the piston rod 33, the one end 25 of which is connected to the piston part 32 and the other end to a cross head 34 slidably in a guideway 35 on the opposite end of the casting 30 from cylinder 31. The cross head 34 is connected to the arm 28 of the brake roll operating shaft through the link 29 already referred to. In Fig. 9, the two parts 32, 32' of the piston are together so that the piston has its longest stroke. By this construction of piston and cylinder I am able to 30 make use of the same not only for controlling

the length of the working stroke of the piston and piston rod and consequently the amount of working imposed upon the sheet being worked by the brake roll 17, but also for cushioning the working and return strokes of the parts, and also to provide for a nicety of regulation of the cushioning means, all of which renders the machine more flexible and adaptable for various kinds and conditions of work and operation.

70 The piston part 32' has a sleeve 36 extending through the stuffing box in the head of the cylinder and some distance beyond and this sleeve has secured to the end thereof a gear 37, this gear meshing with an elongated pinion 38 on countershaft 39 paralleling the piston rod and sleeve 36. A sprocket wheel 40 is secured to the shaft, through which it is connected to be operated from the hand wheel 41 at the front of the machine by means of a chain 42 connecting the sprocket 40 with a sprocket (not shown) on the hand wheel shaft.

75 Through the mechanism just described the distance between piston parts 32 and 32' can be adjusted from the front of the machine to vary the length of the working stroke. The working stroke of the piston and the working roll is also cushioned at its end, regardless of the length of the stroke, by using the front end of the cylinder as a dash pot, and the movement of the piston is gradually brought to a stop by a gradual closing of the small orifice or orifices through which the air in front of the piston must escape. One way in which this gradual checking can be effected is by the provision of a series of small orifices 43 arranged helically around the end of the cylinder, so that they are successively closed by the piston approaching the end of its stroke. If desired, certain of the orifices can be rendered inoperative by inserting screw plugs therein to close them. By this means a variable cushion effect can be obtained.

80 I also provide for a cushioning of the return or down stroke of the roll 17 under the action of gravity, by making use of the exhaust air from the back of the piston 32, 32'. Through the exhaust port 44 from the relay valve mechanism R, Fig. 7; which is entirely similar to that shown and described in the patent hereinbefore referred to, the air is led by a conduit 45 to a small cylinder 46 secured alongside main cylinder 31. The ends of the cylinder 46 are open and a piston 47 has a loose fit within the bore of the cylinder, and is operated in unison with the piston 32, 32', by the connection of its rod 48' to an arm 49 bolted to the crosshead 34.

85 The piston 47 is of a length and is so related to the port entering the cylinder from exhaust conduit 45 that it does not block this port during the major portion of the return or down stroke of the brake roll, but in the 90

last of its return, the valve closes the port thereby cushioning the stroke through the imprisoned air, but, because of its loose fit in the cylinder, it allows the imprisoned air 5 to escape at a gradual rate to permit the piston 32, 32' and roll 17 to complete their return.

In the connections between the inlet conduit 50' leading air from the relay valve mechanism R to the cylinder 31, I provide means 10 for adjustably regulating the admission of air to the cylinder and thus control the speed of the working stroke of the brake roll and the speed of the operation of the machine in accordance with the requirements of the work 15 being operated on. Such means consists of two parallel conduits, one an exhaust conduit 48 of relatively large diameter, which exhausts the air very rapidly from the cylinder 20 and thus permits a rapid return of the brake roll, and the other as a conduit 49 of smaller diameter controlled by a spigot or choke valve 50. A choke valve 51 prevents passage 25 of the air through the exhaust conduit 48 while the roll is being raised. When the speed of rise of the roll is to be varied, the valve 50 is adjusted.

The speed adjusting valve 50 may be controlled from the front of the machine to shut 30 off the conduit either partially or entirely through the handle 51', Fig. 1, connected to the valve by suitable intermediate connections, including the shaft 50^a on which the handle is mounted, and connecting rod 50^b 35 connecting a crank arm 50^c on the shaft with the valve 50.

The operation of the relay valve R is controlled by electrical control circuits, the operating circuit of which has in series there- 40 with the electro-magnet 52. The energization of this electro-magnet, operates a small valve, not shown, to admit air to operate the main valve 53 of the air relay mechanism, in the same manner as in the prior patent above 45 referred to.

As in the prior patented construction, the main control circuit including the electro- 50 magnet 52 is completed by the passage of a sheet through the machine, but as shown in the diagram of Fig. 12, I provide a wider 55 range of control by the selector switch panel S, the automatic control switch T and the safety switch W. In the drawings leads for the high voltage line for running the elec- 60 trical motor M for driving the rolls are designated 53 and 54 and the leads from the low voltage battery circuit by 55 and 56. The hold down rolls 20 are insulated from the machine and the guide 21 is grounded with the machine. The pinch rolls 16 are 65 grounded.

Now assume the battery switch 57 closed and the switch 58 thrown to the dot and dash line position shown. The circuit including 70 the battery 59 and electro-magnet 52 is then open at two points, between hold down rolls

and pinch rolls and at the automatic control switch T, assuming there is no sheet in the machine.

If a sheet, as s, is now fed between the hold 75 down rolls and into contact with the pinch rolls, the battery circuit is closed at one of these points, but is still open at the automatic control switch T. This switch T is so related to the first pair of pinch rolls 16 that the circuit is not completed to operate the relay mechanism to admit air to the cylinder and raise the brake roll through its working stroke until the sheet has entered between the first pair of pinch rolls.

To this end, the automatic switch T consists of a bell crank lever pivoted at 60' having a very short arm 60 and a comparatively long arm 61 carrying a contact point 63 adjacent its outer end. The short arm is adapted to bear upon the top of the upper roll 16 of the first pair of pinch rolls through a roller contact 62, being continually urged to this position by a spring 63'. Opposed to the contact point 63 is a spring pressed contact finger 64 urged in one direction, i. e. toward contact 63 by a spring 65, but adapted to be adjusted with reference to said contact by an adjusting screw 66 and locked in place by a lock nut 67. This contact mechanism is insulated from the machine by being mounted on suitably insulated supports. With the distance between contacts 63 and 64 properly adjusted, the circuit is open at this point when the pinch rolls are running idly, but as soon as a sheet enters between the rolls, the upper roll is slightly raised which turns the lever 60, 61 around its pivot and, because of the great difference in the length of the arms, moves the contact point a relatively greater distance, to close the circuit. The brake roll will now be lifted to its working position and the circuit will be maintained closed until the sheet leaves the hold down rolls. This operative position of the parts is shown in Fig. 5.

If it is desired to subject the sheets being worked to action of the working roll to the very end of the sheets, the selective switch 58 is thrown to the dotted line position, and another circuit including the battery and elec- 110 tromagnet but not including the hold down rolls as an element thereof will be closed but only when the automatic control switch T is closed by the entry of the sheet between the first pair of pinch rolls 16.

If the contacts 63, 64 should happen to be wrongly adjusted to each other, so that the circuit is normally closed at the automatic control switch, when the switch 58 is at its dotted line position, the operating circuit through electromagnet and battery would be closed and the brake roll held in raised position, which would prevent feeding a new sheet to the pinch rolls and thus call the attention of the operator to the fact that the 120 125 130

switch points 63 and 64 might possibly need adjustment.

The safety switch mechanism W is adapted to simultaneously open both the high voltage circuit for running the rolls 12, 16 of the machine and the battery circuit for controlling the operation of the brake roll 17. It comprises a pivoted switch arm 65 carrying knife switch contacts for cooperating with opposed relatively stationary contacts. See Fig. 6. The switch arm is pivoted at 22' adjacent the upper one of the first pair of pinch rolls and has a short arm 65' curved around the roll and having its end extend down in the space between the upper rolls 16 of the pairs of pinch rolls. Pivotally carried by the end of the short arm 65' is a feeler member 66 which extends down between the rolls and substantially fills the space between the rolls at their point of closest approach.

The purpose of this arrangement will be made clear by the following: In a machine of this class it sometimes happens that after the front edge of a sheet has passed the first pair of pinch rolls in its passage through the machine, it will curl up and instead of passing between the next pair of pinch rolls, it will pass upwardly between the pinch rolls, and if the machine is not stopped, it may wrap itself around the roll until the roll and sheet are welded together, and the machine has to be taken down and the roll reground. The novel safety switch construction is designed to stop the machine, in such event, before any damage can be done. As soon as the front edge of such recalcitrant sheet engages the feeler member 66, it will press it upwardly, swing the switch arm 65 on its pivot to the dotted line, Fig. 6, and open both the main high voltage line and the battery circuit, to bring the machine to a complete stop. The switch arm 65 is also provided at its upper end with a handle to permit its manual operation, if desired.

For convenience in installation and operation, the switch arms are located on a bracket 68 secured to the front of the frame of the machine. This bracket is adjustably secured to permit proper location of the short arms 65 of the switch levers with relation to the pinch rolls through the slot and screw connection 69.

To secure an even and firm gripping of the pinch rolls 16 upon a sheet being fed, the opposed rolls are forced toward each other under high pressure when a sheet is located between them, thus firmly gripping the sheet throughout its width and exerting an even effort thereon, preventing slippage. According to my invention, I am able to readily adjust this pressure to adapt the rolls for different thicknesses of sheets, and also to so regulate the pressure means that a large part thereof is not active during the idle running of the rolls, thereby avoiding unnecessary wear on the rolls, yet insuring the presence

of adequate pressure when the rolls are operating on a sheet. To prevent deflection of the rolls under this pressure, a pair of spaced bearing cages 70 each carrying three large rolls 70' bearing against the under side of the pinch rolls, are provided. To prevent longitudinal tilting of the pairs of pinch rolls, i. e. to prevent one pair of rolls being depressed more than the other, I provide each of these cages with knife edge bearing seats 71, the bottoms of these seats being parallel to the longitudinal axis of the machine and the general direction of travel of the sheets through the machine. Cooperating with these seats are the knife edges 72, supported on the deep transverse beam member 25 of the base frame. These seats and knife edges are of a length to positively preclude any longitudinal tilting of the bearing cages 70, and consequently any relative vertical displacement of the two pairs of pinch rolls.

Above the rolls 16 and arranged in opposed relation to the lower bearing cages 70, are similar bearing cages 73 carrying rolls 73' and connected by an equalizer bar 74, having its central portion depressed and forming a socket 75 to receive the end of the pressure applying means and its outer ends bearing centrally upon the cages 73 through ball bearings 76.

The pressure applying and adjusting means are mounted upon a heavy arched pressure bridge 77 seated and firmly secured down upon the opposite side frame members 13. A pressure head 78 is mounted centrally upon the bridge, this pressure head carrying a heavy pressure applying pin 79 guided by an opening 80 in the bridge 77, and having its lower rounded end seated in the central socket 75 of the equalizer bar 74. A suitable wear resisting plate 81 may be inserted between the end of the pin and the bottom of the socket.

The main pressure is transmitted to the pin 79 by a powerful coil spring 82 which acts through a collared sleeve 83 threaded to an intermediate threaded portion of the pin, one end of the spring bearing upon the collar of the sleeve and the other end bearing against the pressure head 78. To vary the tension of the spring 82 the pressure head is vertically adjustable. To this end it is mounted upon two heavy studs 84 projecting upwardly from the bridge 77 on opposite sides of the pin 79, their upper threaded ends extending through the head, and being engaged by nuts 85, rotatably but non-translatable mounted in the head. The nuts are provided on their peripheries with worm wheels 86, which are, in turn, engaged by worms (concealed) on a worm shaft 88 operatable by a large hand wheel 89. Thus operation of the hand wheel will adjust the head up or down to vary the tension of the spring 82.

When the parts are properly adjusted and

the rolls are running idle, the collar on the sleeve 83 is bottomed on the recess in the bridge receiving it, and the full tension of the spring is not transmitted to the pin. The only pressure applied to the rolls at such times is the relatively small pressure, which can be supplied by turning the small manually-operated hand wheel 90 secured to the projecting upper end of the pin. This is purposely made small, so that excessive pressure cannot be applied. This reduced pressure is applied when the sleeve, which is non-rotatably mounted in the head 78 is bottomed, to insure that substantially the full pressure of the spring 82 will be applied when a sheet is fed between the rolls and a proper tractive effect obtained. When the pin has been properly adjusted by the hand wheel 90 it may be locked in such adjusted position by the lock nut 91 engaging the threaded upper end of the pin and the end of the sleeve.

It will be seen that the entire pressure means including the head 78, pin 79, sleeve spring 82 and sleeve 83 may be readily bodily removed and replaced as a unit, when desired, thus affording easy access to the parts for replacement or repair.

From the foregoing detailed description, it is believed that the operation of the machine as a whole will be apparent, and further description of its operation is believed unnecessary. It will be seen that I have provided a machine which is very compactly arranged, in which the various parts are readily accessible, and replaceable or repairable if the need arises, in which the control of the machine is centralized at the front of the machine, and which is adapted for a wide variety of work, and for automatically turning out the work, when adjusted for a given condition, at a very rapid rate. The various novel features and combinations which contribute to the general efficiency, ruggedness and adaptability of the machine are particularly pointed out in the appended claims.

What I claim is:

1. A roller leveler machine comprising two pairs of pinch rolls provided with backing rolls, a seat parallel to the plane passing through the axis of two of said rolls on the same side of the path of a sheet through the rolls, a cradle for carrying the backing rolls for said pinch rolls and having a knife edge support on said seat and extending transversely of said pinch rolls to prevent tilting of the same.

2. A roller leveler machine comprising a pair of opposed pinch rolls and a pair of hold down rolls spaced therefrom, and a sheet bending element adapted to be moved transversely of the path of a sheet extended between said rolls for giving said sheet a loop bend, said hold-down rolls being axially offset from each other, with the upper roll nearest the pinch rolls.

3. A roller leveler machine comprising a pair of pinch rolls, a sheet bending element adapted to be moved transversely to the path of a sheet being fed to the machine, means for so moving said sheet responsive to the displacement of one of said pinch rolls due to the entry of the sheet between said rolls. 70

4. A roller leveler machine comprising a pair of pinch rolls between which a sheet is adapted to pass, a sheet bending element 75 adapted to be moved transversely to the path of said sheet, means for so moving said bending means after the sheet has been entered between the pinch rolls, and means operative to cause a stoppage of said moving means and the machine should a sheet start to wrap around a pinch roll. 80

5. A roller leveler machine comprising a pair of opposed pinch rolls, means for backing said rolls to apply pressure to said opposed rolls, said means normally applying relatively light pressure during idle movement of the rolls, but rendered operative automatically upon the entry of a sheet between said rolls to apply heavy pressure. 85 90

6. A roller leveler machine comprising a pair of pinch rolls, hold down rolls spaced therefrom, a sheet bending element movable between said spaced rolls transversely to the path of the sheet, means for rapidly approaching and receding said element from its operative position, and means for gradually checking said movement at the end of each stroke. 95

7. A roller leveler machine comprising a 100 sheet bending element movable transversely to the path of the sheet being worked, a fluid-actuated means for moving said element in its operating stroke, including a fluid-check for cushioning the final part of said stroke. 105

8. A roller leveler machine comprising a sheet bending element movable transversely to the path of the sheet being worked, a fluid-pressure means including as elements thereof, a piston and cylinder for moving said element to its operative position, one of said fluid-pressure elements being adjustable to vary the length of stroke of said bending element. 110 115

9. A roller leveling machine comprising a sheet bending element movable transversely to the path of a sheet being worked, fluid-pressure means for moving said sheet into its operative position, including a piston and cylinder, said piston being adjustable to vary the length of stroke, and forming part of means for cushioning the final portion of said stroke. 120

10. A roller leveling machine comprising a sheet bending element movable transversely to the path of a sheet being worked, fluid-pressure means for moving said sheet into its operative position, means for exhausting said fluid under pressure to permit the ele- 125 130

ment to return rapidly to inoperative position, and means for automatically throttling the exhaust near the end of said return movement to cushion the same.

5 11. A roller leveler machine comprising a pair of opposed pinch rolls and a pair of hold-down rolls spaced therefrom and a sheet bending element adapted to be moved transversely of the path of the sheet which is extended between said rolls for giving said sheet a loop bend, said hold down rolls being positioned one above the other, the axis of the upper hold-down roll being positioned closer to the plane of the opposed pinch rolls than the axis of the lower hold-down roll.

10 12. A roller leveler machine comprising a pair of opposed pinch rolls, means normally urging said rolls against each other to apply heavy pressure to a sheet of material inserted therebetween, and means for rendering said pressure applying means partially inoperative upon removal of the sheet from between said pinch rolls.

15 13. A roller leveler machine comprising a pair of opposed pinch rolls, a cradle having rolls mounted therein and means associated with the cradle normally urging said pinch rolls towards each other to apply heavy pressure thereto when a sheet of material is inserted therebetween, a stationary support and a projection on said last mentioned means adapted to engage said support when the sheet is removed from between the pinch rolls for relieving the pressure of the same on the opposed rolls.

20 14. In combination with a roller leveler machine comprising a sheet bending element movable transversely to the path of the sheet being worked, of a fluid pressure means including as elements thereof a piston and cylinder for moving said element to its operative position, said piston being adjustable to vary the length of stroke and forming a part of means for cushioning the final portion of said stroke, and means externally of the cylinder and remote from the same for adjusting said piston.

25 15. A roller leveler machine comprising a pair of opposed pinch rolls, unitary removable means normally urging said rolls against each other to apply heavy pressure to a sheet of material inserted therebetween, including means for adjusting the amount of pressure between the rolls and means for rendering said pressure applying means partially inoperative upon removal of the sheet from between said pinch rolls.

30 16. A roller leveler machine comprising a pair of opposed pinch rolls, means normally urging said rolls against each other to apply heavy pressure to a sheet of material inserted therebetween, means for regulating the amount of pressure between said pinch rolls and adjustable means for rendering said pressure applying means partially inopera-

tive upon removal of the sheet of material from between said pinch rolls.

In testimony whereof I hereunto affix my signature.
